UNITED STATES PATENT OFFICE

2,292,178

ELECTRIC SWITCH

Fred H. Travers, New Britain, Conn., assignor to
 General Electric Company, a corporation of
 New York

Application June 7, 1939, Serial No. 277,824

5 Claims. (Cl. 219—20)

The present invention relates to electric switch-
 es, and more particularly to an improved con-
 struction and arrangement in electric switches
 of the type used for controlling the heat output
 of multiple element heater units.

It is an object of this invention to provide a
 switch construction having a simplified contact
 arrangement for controlling the connections of
 a multiple element heater unit with a power
 supply to provide a plurality of different heat
 outputs and to completely isolate the heater unit
 from the power supply when the switch is in
 open circuit position.

Another object of this invention is to provide
 an improved circuit controller including inter-
 connected switches for controlling the energiza-
 tion of a plurality of heater units and for limit-
 ing the maximum power which may be consumed
 by the heater units associated with the inter-
 connected switches.

Further objects and advantages of the present
 invention will become apparent as the following
 description proceeds, reference being had to the
 accompanying drawings, in which Fig. 1 is a plan
 view of a circuit controller embodying the inven-
 tion; Fig. 2 is an elevational view, partially
 broken away, of the controller of Fig. 1; Fig. 3
 is an exploded view in perspective showing one
 of the positioning and actuating mechanisms
 employed in the controller of Fig. 1; Fig. 4 is a
 sectional view taken along the lines 4—4 of Fig.
 2, but with the rotatable contact structure dis-
 placed 90 degrees in a clockwise direction as
 viewed in Fig. 1, and Figs. 5 to 13 are schematic
 diagrams showing the circuit controller of Figs.
 1 to 4 in a number of its operative positions and
 illustrating the condition of the heater circuits
 associated therewith.

In the drawings I have shown a circuit con-
 troller embodying my invention as comprising
 a pair of switches designated generally by nu-
 merals 10 and 11. The switches are supported
 on a base 12 of suitable insulating material
 which is provided with a pair of substantially
 cylindrical recesses 13 for receiving and partially
 housing the parts of the switches. Bosses 14
 are molded integrally with the base 12 at each
 end thereof and form means for supporting a
 mounting strap 15 in spaced relation to the
 upper face of the base. The strap is secured to
 the base by suitable bolts 16. Since both of the
 switches 10 and 11 are of identical construction
 only one will be described and corresponding
 parts will be designated by the same numerals.

An operating spindle 17 passes through an

opening in the mounting strap 15 and has its
 lower end received in a suitable bearing sleeve
 18 secured to the base at the center of the recess
 13. The spindle is provided at its outer end
 5 with an operating knob 19 which is secured
 thereto in any suitable manner. The movable
 contacts of the switch are secured to a disk 20
 of insulating material which is assembled on a
 flanged sleeve 21 with an insulating washer 22,
 10 a metal spacing washer 22a and a driving mem-
 ber 23. This disk assembly is mounted on the
 spindle for rotation relative thereto.

In the drawings I have shown a positioning
 means for the disk assembly as comprising a
 15 member 24 secured to the lower face of the
 mounting strap and having four equally spaced
 projections 25. A specially shaped pawl member
 26 surrounds the spindle and has an eccentric
 portion arranged to lie between a pair of the
 20 projections 25. The pawl 26 has a depending
 lug 27 which is received in an elongated opening
 28 in the disk driving member 23, so that the
 disk is retained against rotation with respect to
 the switch body as long as the pawl member 26
 25 engages one of the projections 25 of the member
 24. In order to release the pawl, a cam member
 29 fixed eccentrically to the spindle engages the
 walls of an opening in the pawl 26, so that rota-
 tion of the spindle is effective to move the pawl
 transversely of the axis of the spindle and re-
 lease it from the projections 25.

The driving connection between the disk as-
 sembly and the spindle is accomplished by a
 double helical spring 30 which is retained be-
 35 tween a pair of metal plates 31 and 32 fixed to
 the spindle. A bearing washer 31a of insulating
 material is assembled on the spindle between the
 upper surface of the plates 31 and the disk 20
 and a metal spacing washer 32a is placed on the
 40 spindle between the plate 32 and the upper flange
 of the bearing sleeve 18 to properly position the
 spindle assembly relative to the body and sta-
 tionary contacts. A pair of axially extending
 arms 33 and 34, formed integrally with the plate
 45 31 and the driving member 23 respectively, are
 positioned between a pair of spaced laterally
 extending spring arms 35 formed on the opposite
 ends of the helical spring. With this construc-
 tion it is seen that the arm 33 is secured to the
 spindle and the arm 34 to the disk assembly with
 the spring 30 forming the driving connection
 between these arms. The member 23 is posi-
 tioned on the opposite side of the disk 30 from
 the plate 31 so that the arm 34 passes through
 an opening 36 in the disk and engages the walls

thereof to form a driving connection with the disk. When the spindle is rotated the arm 33 moves one arm of the spring while the other arm of the spring is retained by the depending arm 34 on the driving member 23. When the spindle has been moved the required amount, which in the present case is approximately 90 degrees, the pawl 26 is released from the projections 25 and the driving member and disk are free to rotate under the influence of the spring arm having engagement with the arm 34 until the pawl 26 engages the next projection on the member 24.

With the construction thus far described, it is apparent that the disk 20 may be moved with a snap action to four different equally spaced positions by rotation of the operating knob 19. In accordance with the present invention a novel arrangement of fixed and movable contacts is also provided for accomplishing the desired electrical connections between the heater units and the supply lines. Each switch is provided with two sets of fixed contacts, one of which is arranged to engage the upper surface of the disk and the other of which is arranged to engage the lower surface. In the construction illustrated the upper set includes three contacts 37, 38 and 39 and the lower set includes four contacts designated by the numerals 40—43, inclusive. Each contact is provided with a terminal portion which is secured to the face of the switch body by a flanged internally threaded sleeve 44 which receives a binding screw 45 for securing circuit wires thereto. Openings 46 formed in the base 12 adjacent the terminal portions of the fixed contacts permit top wiring of the switches; keep the wires within the confines of the base and provide a strain relief for the connections. The upper surface of the disk is provided with arcuate contacts 47 and 48 and the lower surface of the disk is provided with arcuate contacts 49 and 50. The spacing of the fixed contacts and the angular extent and spacing of the arcuate contacts which are important features of the present invention can best be explained in connection with a heater circuit with which the controller of the present invention may be used to particular advantage. This circuit is shown with the switches 10 and 11 in various circuit-controlling positions in the schematic diagrams of Figs. 5 to 13, inclusive. In order to simplify these figures the arcuate contacts secured to the lower face of the disk 20 have been shown on a separate disk 20a, and the portions of the circuit which carry current in each of these diagrams are shown in heavier lines, so that the circuit changes accomplished by the switches are readily observed by an inspection of the drawings.

In the diagrams the switches 10 and 11 of the circuit controller are shown connected to control the energization of a pair of heater units designated generally by numerals 51 and 52 from a pair of supply lines 53 and 54. Each of the heater units comprises a pair of resistance elements 55 and 56 having a common terminal at one end and separate terminals at the other end. Heater units of this type may be energized to supply a high, a medium or a low heat output by selectively connecting the heater terminals to a single supply voltage. In the drawings I have shown the heater unit 51 and the heater unit 52 connected to the switches 10 and 11 respectively, in the following manner: The common terminal is connected to contact 37 of the upper set of fixed contacts, one of the separate ter-

minals is connected to the contact 39 of the upper set and to contact 43 of the lower set, and the other separate terminal is connected to contact 42 of the lower set. The contact 40 of the lower set of fixed contacts of the switch 10 is connected directly to the supply line 54, while the contact 40 of switch 11 is connected directly to supply line 53. The contact 38 of the upper set of fixed contacts of each switch is connected by conductor 57 to the fixed contact 41 of the lower set of fixed contacts of the other switch. The fixed contact 41 is positioned adjacent the contacts 40 and may be connected thereto by one of the arcuate contacts 49 or 50 in all but the high heat position of the switch so that power from one of the supply lines is supplied to each switch through a pair of angularly spaced contacts on the other switch except when the other switch is in its high heat position. The advantage of this arrangement will become apparent as the description of the circuit proceeds.

In Fig. 5 both of the switches are in their "off" position and both of the heating units 51 and 52 are completely isolated from the supply lines. In Fig. 6 the switch 11 has been rotated 90 degrees in a clockwise direction to its "high" heat position. With the switches in this position, a circuit is completed from supply line 53 to fixed contact 38 of switch 11 through fixed contact 40 of switch 11, arcuate contact 49, the fixed terminals 42 and 43, the resistor elements 55 and 56 of heater unit 52, fixed contact 37, and arcuate contact 48 to fixed terminals 38 of the switch 11. A circuit is completed from contact 38 to the other supply line 54 through conductor 57, angularly spaced fixed contacts 40 and 41 and the arcuate contact 50 of the switch 10. With the switch 11 in its high heat position, as shown in this figure, it is seen that it would be impossible to energize the heating unit 51 associated with the switch 10 since the fixed contact 41 of the switch 11 is insulated from the fixed contact 40 of that switch which is the only contact of the two switches connected directly to the supply line 53. In Fig. 7 the switch 11 has been rotated 90 degrees in a clockwise direction to its medium heat position. In this position the element 56 of heater unit 52 is energized through a circuit which is apparent from the drawings. In Fig. 8 the switch 11 has been given another 90 degrees turn in a clockwise direction to its low heat position in which the elements 55 and 56 of its associated heater elements 52 are connected in series across the supply lines 53 and 54. From the preceding description it is seen that the fixed contact 38 which supplies power selectivity to the upper contacts 37 and 39 through the arcuate contacts 47 and 48 is positioned between contacts 37 and 39 and nearer to the contact 37 so that power may be supplied to the common terminal of the heater unit in two positions of the switch, namely, the "high" and "medium" heat positions, while the fixed contact 39 is connected to the contact 38 only in the "low" heat position of the switch. In Fig. 9 the switch 10 has been rotated 90 degrees in a clockwise direction to its "high" heat position and switch 11 has been rotated in a counterclockwise direction to its medium heat position. With the switches in this position it is seen that the elements of the unit 51 are connected to the line through a circuit including the spaced contacts 40 and 41 of switch 11 which are bridged in the medium heat position of the switch by arcuate contact 49. With the switch 10 in its "high" heat position, however, the heat-

er unit 52 is not energized even though the switch 11 is in its "medium" heat position since, as previously pointed out, only one power supply line is connected directly to each switch and the other power supply line is connected thereto through a pair of spaced contacts on the other switch. In this case, the spaced contacts 40 and 41 of the switch 10 are not bridged by either of the arcuate contacts 49 or 50. In Fig. 10 the switch 10 is in its "low" heat position and the switch 11 in its "off" position. Here the condition of the heater units 51 and 52 is exactly the reverse of that described in connection with Fig. 7. In Fig. 11 both switches are in the medium heat position and both heater units are energized, the circuit for each one being completed through the angularly spaced contacts 40 and 41 of the switch controlling the other heater unit; the fixed contacts being bridged by arcuate contact 49. Fig. 12 shows the switch 10 in its high heat position and the switch 11 in its open circuit position, which is the opposite of that shown in Fig. 6. Fig. 13 shows both switches in their high heat positions and as is clear from this diagram neither of the heater units is energized since the spaced contacts 40 and 41 of both switches are insulated from each other, so as to disable the heater unit associated with the other switch.

In the preceding description the switches have been described as having two arcuate contacts 47 and 48 on the upper face of the disk 20. However, it is clear from an inspection of the diagram that the switches are operative if this contact is made in one piece. With a single arcuate contact on the upper face of the disk there is a tendency for the leading edge of the arcuate contact on the upper surface of the disk to make contact with the fixed contact 39 before the arc is extinguished between the arcuate contact 49 and the fixed contact 40 when the switch is rotated from "medium" to "low" heat position; thus resulting in a momentary short circuit. To avoid this the upper arcuate contact is made in two sections 47 and 48 of unequal length so that the power supply line 54 which is indirectly connected to the fixed terminal 38 of the switch 11 is not connected to the arcuate contact 48 in the "medium" heat position of the switch 11 and fixed contact 39 is offset slightly in a counter-clockwise direction to engage the arcuate contact 47 in the "low" heat position of the switch.

While in the preceding description I have disclosed a circuit controller comprising two interconnected switches for controlling a pair of plural element heater units, it is apparent that the simplified construction of the switches may also be used to advantage for controlling a single three-heat unit. For example, if switch 10 were to be used for controlling a single unit, the interconnecting conductors 57 would be omitted and the fixed contact 38 would be connected directly to the other supply line 53. In this case the fixed contact 41 and the arcuate contact 50 would not be used.

With the circuit controller of the present invention the switch structures employed are simple and easily manufactured using fixed contacts of uniform construction and arcuate contacts positioned on the disk to provide the selective connection to the heater units with the power supply lines. The separate arcuate contact 50 provides means for energizing one of the interconnected switches when the other is in its "off" position, and the arrangement of the fixed con-

tacts is such that the heater unit is completely isolated from the power supply line when the switch with which it is associated is in its open circuit position. The spaced contacts of one switch which usually supply power from one of the supply lines to the other switch are open circuited when the one switch is in its high heat position so that it is impossible to draw more than a predetermined maximum amount of power from the supply lines even though the switches of both units are in the closed circuit position. This feature is particularly desirable in controllers designed for use with hot plates which are plugged into convenience outlets of house wiring systems.

What I claim as new and desire to secure by Letters Patent of the United States, is:

1. An electric circuit controller for controlling the energization of a pair of two element heater units from a pair of supply lines, comprising an electric switch having an open circuit position and three closed circuit positions associated with each of the heater units for controlling the heat output thereof, each of said switches having a rotatable contact structure including a support of insulating material having arcuate contact means mounted on one face thereof and a pair of arcuate contacts of different angular extent mounted in insulated relation on the other face thereof, a first stationary contact on one of said switches connected to one power supply line and arranged to engage the arcuate contact of greater angular extent on said other face of said support in the three closed circuit positions thereof, a second stationary contact of said one switch having engagement with the arcuate contact means on said one face of said support in the three closed circuit positions of said one switch, said second stationary contact being connected to the other supply line through a pair of angularly spaced stationary contacts of the other of said switches, said angularly spaced stationary contacts being electrically connected by the arcuate contact of lesser extent of said other switch in the open circuit position of said other switch and being electrically connected by the other of the pair of arcuate contacts of said other switch in all but one closed circuit position of said other switch whereby the heating unit with which said one switch is associated may be energized only through cooperating contacts of said other switch when said other switch is in any but said one closed circuit position.

2. A circuit controlling device for controlling the energization of a pair of two element heater units having a plurality of terminals from a pair of supply lines, comprising an electric switch associated with each of the heater units for controlling the heat output thereof, each of said switches having a first fixed contact for direct connection with a different one of the power supply lines, a second fixed contact and a third fixed contact, the third fixed contact of each of said switches being electrically connected to the second fixed contact of the other of said switches, other fixed contacts on each of said switches for connection with the terminals of its associated heater unit, each of said switches having a rotatable contact structure including a plurality of arcuate shaped contacts for connecting selectively said other fixed contacts with said first and third fixed contacts, and a separate arcuate contact on each of said switches for bridging said first and second fixed contacts when said switches are in their open circuit positions.

whereby the heater unit associated with either switch may be energized when the other switch is in its open circuit position.

3. A circuit controlling device for controlling the energization of a pair of two element heater units having a plurality of terminals from a pair of supply lines, comprising an electric switch including a rotatable contact structure having a plurality of circuit controlling positions associated with each of the heater units for connecting the elements thereof to the supply lines for different heat outputs, one of said switches having a plurality of fixed contacts connected to the terminals of its associated heater unit, a fixed contact connected directly to one power supply line and another fixed contact connected to the other of the supply lines through a pair of angularly spaced fixed contacts on the other of said switches, the rotatable contact structure of said one switch including a plurality of arcuate contacts for connecting selectively the fixed contacts connected to the terminals of its associated heater unit with the fixed contacts connected to the power supply lines, the rotatable contact structure of the other of said switch having a plurality of arcuate contacts of such angular extent and spacing as to bridge said pair of angularly spaced fixed contacts in all but the high heat position of said other switch whereby the heater unit associated with said one switch may be energized when the rotatable contact structure of said other switch is in any but its high heat position.

4. A circuit controlling device for controlling the energization of a pair of two element heater units having a plurality of terminals from a pair of supply lines, comprising a multi-position electric switch associated with each of the heater units for controlling the heat outputs thereof, each of said switches having a first fixed contact for direct connection with a different one of the power supply lines, a second fixed contact and a third fixed contact, the third fixed contact of each of said switches being electrically connected to the second fixed contact of the other of said switches, other fixed contacts on each of said switches for connection with the terminals of its associated heater unit, each of said switches having a rotatable contact structure

including a plurality of arcuate contacts for connecting selectively said other fixed contacts with said first and third fixed contacts and for bridging said first and second contacts in the medium and low heat positions of said switches, and a separate contact on the rotatable contact structure of each of said switches for bridging said first and second contacts thereof when said switches are in their open circuit position, the spacing of said fixed contacts and the arcuate length and spacing of said arcuate contacts being such as to completely isolate the heater unit from the supply lines when the movable contact structure of the switch with which it is associated is in its open circuit position.

5. A circuit controlling device for controlling the energization of a pair of two element heater units having a plurality of terminals from a pair of supply lines, comprising a multi-position electric switch associated with each of the heater units for controlling the heat output thereof, each of said switches having a plurality of fixed contacts arranged in two sets lying in different planes, a first fixed contact in one set for direct connection with a different one of the power supply lines, a second fixed contact in the other set and a third fixed contact in said one set, the third fixed contact of each of said switches being electrically connected to the second fixed contact of the other of said switches, other fixed contacts in each set of each of said switches for connection with the terminals of its associated heater unit, each of said switches having a rotatable contact structure including a plurality of arcuate contacts arranged in two different planes for connecting selectively said other fixed contacts with said first and second fixed contacts and for bridging said first and third contacts in the medium and low heat positions of said switch and a separate arcuate contact on the rotatable contact structure of each of said switches for bridging the first and third contacts thereof when said switches are in their open circuit position whereby the heater unit associated with either of said switches may be energized when the other switch is in any but its high heat position.

FRED H. TRAVERS.
